US00D624582S

(12) **United States Design Patent**
Müller-Lancé et al.

(10) **Patent No.:** US D624,582 S
(45) **Date of Patent:** ** Sep. 28, 2010

(54) **TYPE FONT**

(75) Inventors: **Joachim Müller-Lancé**, San Francisco, CA (US); **George Arriola**, San Francisco, CA (US)

(73) Assignee: **Sony Ericsson Mobile Communications AB**, Lund (SE)

(**) Term: **14 Years**

(21) Appl. No.: **29/362,656**

(22) Filed: **May 28, 2010**

(51) **LOC (9) Cl.** 18-03

(52) **U.S. Cl.** D18/24

(58) **Field of Classification Search** D18/24-33;
101/398, 399

See application file for complete search history.
